UNITED STATES PATENT OFFICE

2,582,906

GARBAGE CAN RACK

Russell C. Heldenbrand, New Iberia, La.

Application September 19, 1946, Serial No. 698,039

5 Claims. (Cl. 211—71)

1

This invention relates to improvements in garbage can racks.

An object of the invention is to provide an improved portable garbage can rack which will be so constructed that the same may be driven into the ground to rotatably and removably support one or more disposal garbage cans.

Another object of the invention is to provide an improved rotatably supported garbage can rack including a vertically extending fixed pipe standard having a bearing formed adjacent its lower end, and a sleeve mounted for rotation thereon having wedge-shaped mounting brackets secured to its opposite sides adapted to be engaged by complementary wedge-shaped supporting brackets on the supported garbage cans, together with arcuate members on said cans disposed below said brackets and adapted to contact the curved outer surface of said sleeve to brace the garbage cans when supported thereon.

Another object of the invention is to provide an improved garbage can rack which will be highly efficient in operation and relatively inexpensive to manufacture and produce.

Other objects will appear as the description proceeds.

In the accompanying drawings which form a part of this application,

Figure 1 is a perspective view of the improved garbage can rack with a pair of oppositely disposed garbage cans supported thereon;

Figure 2 is a side elevation of the rack supporting standard, showing the same positioned in the ground;

Figure 3 is a sectional view through the adjacent ends of the supporting standard and the sleeve pivotally supported thereon;

Figure 4 is a detail front elevation of a portion of the sleeve with a wedge-shaped mounting bracket thereon;

Figure 5 is a front elevation of one of the attaching brackets adapted to be secured to the side of a garbage can;

Figure 6 is a sectional view taken on the line 6—6 of Figure 1, and

Figure 7 is a sectional view taken on the line 7—7 of Figure 1.

Like characters of reference are used throughout the following specification and the accompanying drawings to designate corresponding parts.

In carrying out the invention, there is provided an improved garbage can rack having a vertically extending tubular pipe standard 1 having an annular bearing ring 2 formed about its upper end,

2

and an enlarged ground-engaging bracing disk 3 formed about its lower end having its corners bent downwardly as at 30. The bottom end of the standard 1 is pointed as at 4 to permit the same to be readily driven into the ground until the bracing disk 3 contacts the surface of the ground 5 and the depending corners 30 thereof are embedded in the ground. Anchoring pins 6 are positioned transversely through the lower end of the standard 1 to additionally support the same in the ground. A receptacle 31 will be secured to the pipe standard 1 slightly above the disk 3 to receive a liquid insecticide for preventing ants and other crawling bugs or insects from reaching the garbage pails.

The sleeve 6' upon which the garbage cans 7 are supported is adapted to snugly but rotatably fit over the upper end of the standard 1 with its lower end bearing on the bearing 2 on said standard 1.

A handle 8 is secured to the upper end of the sleeve 6' for rotating the same.

A pair of oppositely disposed downwardly tapered wedge-shaped mounting brackets 9 and 10 are suitably secured on the central portion of the sleeve 6', and are adapted to be engaged by suitable complementary supporting brackets 15 on the garbage cans 7.

In Figure 5 of the drawings there is illustrated the supporting bracket 15 carried by a vertical body or attaching strip 11 that is apertured at 12 and 13 to receive securing rivets 14 for attaching the same to a garbage can 7. The bracket 15 is formed with the inwardly directed arcuate ears 16 and 17 whose opposite inner surfaces are downwardly and outwardly tapered to lock over the correspondingly tapered bracket 9 on the sleeve 6'.

An arcuate member 18 is secured at the lower end of the body 11 by means of the rivet 19 and when the garbage can 7 is in position on the sleeve 6', said arcuate member 18 will engage the outer surface of the sleeve 6' to positively lock and support the garbage can in position.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In a receptacle supporting rack, a vertical

standard, an elongated sleeve rotatably mounted on the standard, a bracket secured to the sleeve, a complementary bracket adapted to be secured to a receptacle and releasably engaging said sleeve bracket, and an arcuate member in spaced vertical relation below the brackets and partially embracing and frictionally engaging said sleeve, said arcuate member being adapted to be secured to the receptacle.

2. The combination of claim 1, including a bearing ring on said standard supporting said sleeve.

3. A receptacle rack, comprising a vertical standard adapted to be supported in the ground, anchoring means thereon, a bearing ring on said standard, an elongated sleeve rotatably mounted on the standard and supported on the ring, diametrically opposed brackets secured to the sleeve, complementary brackets adapted to be secured to a pair of receptacles, said complementary brackets releasably engaging said sleeve brackets, a pair of arcuate members disposed below the brackets and partially embracing and frictionally engaging diametrically opposed portions of said sleeve, said members being adapted to be secured to the pair of receptacles.

4. In a receptacle rack, a vertical standard, an elongated sleeve rotatably mounted on the standard, a mounting bracket secured to the sleeve, an attaching strip adapted to be secured to a receptacle, a complementary bracket secured to the strip and releasably engaging the first mentioned bracket, an arcuate member secured to the

strip and partially embracing and bearing against the sleeve at a position below the first mentioned bracket.

5. In combination, a vertical standard, an elongated sleeve rotatably mounted on the standard, a pair of mounted brackets secured at diametrically opposed positions to the sleeve, a pair of receptacles each having a bracket secured thereto that is complementary to one of the brackets on the sleeve and detachably engaging the same, each of said receptacles also having an arcuate member secured thereto that partially embraces and bears against the sleeve at a position below the first mentioned brackets, said arcuate members engaging diametrically opposed positions of the sleeve.

RUSSELL C. HELDENBRAND.
